UNITED STATES PATENT OFFICE.

HERBERT E. ENSLIN, OF MALDEN, MASSACHUSETTS, ASSIGNOR TO UNITED SHOE MACHINERY COMPANY, OF PATERSON, NEW JERSEY, A CORPORATION OF NEW JERSEY.

MACHINE FOR LACING SHOE-UPPERS.

1,181,068.

Specification of Letters Patent. Patented Apr. 25, 1916.

Application filed February 15, 1915. Serial No. 8,333.

To all whom it may concern:

Be it known that I, HERBERT E. ENSLIN, a citizen of the United States, residing at Malden, in the county of Middlesex and State of Massachusetts, have invented certain new and useful Improvements in Machines for Lacing Shoe-Uppers; and I do hereby declare the following to be a full, clear, and exact description of the invention, such as will enable others skilled in the art to which it appertains to make and use the same.

The invention relates to machines for lacing shoe uppers in which a series of needles or spindles are arranged to pass a series of loops of lacing cord through the eyelet holes of an upper.

In machines of this type the needles are usually mounted in a series of needle carrying blocks which are laterally adjustable to vary the spacing of the needles in accordance with the spacing of the eyelets of the upper to be laced.

The object of the present invention is to provide novel and improved means for supporting and guiding the needle carrying blocks so that they will be accurately maintained in position to properly coöperate with the other parts and mechanisms of the machine.

To this end the invention comprises the features of construction and combinations of parts hereinafter described and referred to in the claims.

The invention will be readily understood from an inspection of the accompanying drawings and the following detailed description of the mechanism illustrated therein.

In the drawings, Figure 1 is a front elevation showing the carrier in which the looper needles and coöoperating looper fingers are mounted; Fig. 2 is a plan view showing the front end of the carrier with the slide in which the looper fingers are mounted removed; and Fig. 3 is a vertical sectional view through the front end of the carrier.

In the drawings the invention is shown as embodied in an upper lacing machine having substantially the construction and mode of operation of the machine shown and described in Patent No. 1,030,573, June 25, 1912, and Patent No. 1,030,547, June 25, 55 1912. In this machine a series of loops of

lacing cord is held by a series of looper needles and a coöperating series of looper fingers in position to be passed through the eyelet holes of an upper. The needles and looper fingers are mounted in a vertically movable carrier and coöperate with a shuttle or cord carrying needle and with a knot tying mechanism to form, insert and tie the lacing cord. In the drawings the carrier in which the needles and looper fingers are mounted is indicated at 2. The looper needles 4 are secured in spindles 6 which are mounted in needle carrying blocks 8 adjustably supported in the forward end of the carrier. Each needle block is provided with a depending lug 10, the rear face of which engages and is guided by the front face of a guide plate 12 at the forward end of the carrier. The lower surface of the block at the rear of the lug 10 engages and is guided by the upper edge of the guide plate 12. The upper surface of the block engages and is guided by the under surface of a guide bar 14 which extends across the front end of the carrier above the needle blocks. A front plate 16 is secured to the front end of the carrier, and coöperates with the guide plate 12 and guide bar 14 in supporting and guiding the needle blocks. Each block is provided at its rear end with an upwardly extending lug 18, the upper end of which is slotted to embrace one of the looper carrying blocks 20 so that the looper blocks will be adjusted laterally with the needle carrying blocks when the needle carrying blocks are adjusted to vary the spacing of the needles. The needle carrying block at the right in Fig. 1 is secured in fixed position, while the other needle carrying blocks are connected with the upper ends of a series of connected links 22, through which the blocks may be adjusted laterally to properly space the needles, as fully described in Patent No. 1,030,547 above referred to.

In embodying the preferred form of the present invention in a machine having the construction above described, a spring pressed guide bar 24 is arranged to engage the front faces of the lugs 18 on the laterally movable needle blocks, so that the blocks are pressed firmly against the guide plate 12, and so that any tendency for the blocks to drop away from the under surface of the bar 14, due to the wear of the parts

or to any slight play between the blocks, and the guiding surfaces, is effectively resisted. The bar, therefore, acts to maintain the needles of the series in accurate alinement, and 5 to hold them firmly in position to properly coöperate with the shuttle or cord carrying needle and other coöperating parts of the machine. As shown, the spring pressed guide bar 24 is secured to two studs 26 10 which are mounted to slide in the cross-bar 14, and the bar is forced firmly against the lugs 18 and the movable needle blocks by the springs 28 which surround the studs and are interposed between the bar 24 and the 15 rear face of the cross bar 14. The bar 24 is cut away at 30, so that it does not engage the fixed needle block.

While it is preferred to employ the specific construction and arrangement of parts 20 shown and described in embodying the invention in the machine of the patents referred to, it will be understood that this construction and arrangement is not essential to the broader features of the invention, 25 and may be varied or modified as found desirable or best suited to the construction of the machine in which it is to be embodied.

Having explained the nature and object 30 of the invention, and specifically described one form of mechanism in which it may be embodied, what is claimed is:—

1. A machine for lacing shoe uppers, having, in combination, a plurality of needles arranged to pass a series of loops of lacing 35 cord through the eyelet holes of an upper, a series of needle carrying blocks laterally adjustable to vary the spacing of the needles, a carrier provided with a guideway for the blocks, and spring operated means

for pressing the blocks against a guiding 40 surface of the guideway.

2. A machine for lacing shoe uppers, having, in combination, a plurality of needles arranged to pass a series of loops of lacing cord through the eyelet holes of an upper, 45 a series of needle carrying blocks laterally adjustable to vary the spacing of the needles, a carrier provided with a guideway for the blocks, and a spring pressed bar engaging the blocks and pressing them against 50 a guiding surface of the guideway.

3. A machine for lacing shoe uppers, having, in combination, a plurality of needles arranged to pass a series of loops of lacing cord through the eyelet holes of an upper, a 55 series of needle carrying blocks having oppositely facing surfaces, and a carrier for the blocks having guides engaging said surfaces, one of which is spring pressed.

4. A machine for lacing shoe uppers, having, in combination, a plurality of needles arranged to pass a series of loops of lacing cord through the eyelet holes of an upper, a carrier provided with a guide plate at its forward end, a series of needle carrying 65 blocks provided with depending lugs, the rear faces of which engage the front face of the guide plate, a cross-bar on the carrier overlying the needle blocks, a front plate secured to the carrier and underlying the 70 needle blocks in front of the depending lugs, upwardly extending lugs at the rear of the blocks, and a spring pressed bar engaging the front faces of the lugs.

HERBERT E. ENSLIN.
